PRESSURE-OPERATED FEEDING APPARATUS
FOR COMBUSTION LIQUIDS IN AN INTERNAL COMBUSTION CHAMBER

Robert H. Goddard, deceased, late of Annapolis, Md., by
Esther C. Goddard, executrix, Worcester, Mass., assignor of one-half to The Daniel and Florence Guggenheim Foundation, New York, N. Y., a corporation of New York

Application December 11, 1952, Serial No. 325,255

1 Claim. (Cl. 121—43)

This invention relates to internal combustion chambers as used in rockets and other propulsion apparatus. It is common practice to operate such combustion chambers by using a liquid fuel, as gasoline, and a liquid oxidizer, as liquid oxygen. Each of these combustion liquids must be fed to the combustion chamber uniformly and continuously.

It is the general object of this invention to provide improved and simplified apparatus for thus continuously feeding the two combustion liquids.

In the preferred embodiment of the invention, the liquids are fed to the combustion chamber by two separate centrifugal pumps which are operated by a single gas-driven turbine. Liquid nitrogen from a relatively low pressure storage tank is pumped through a heating coil surrounding the combustion chamber and is thereby vaporized. This nitrogen gas, vaporized at much increased pressure, then actuates the turbine which drives the two centrifugal pumps.

The nitrogen pump is preferably of the reciprocating type and is operated by a pneumatic motor which is supplied with compressed air or nitrogen gas through a solenoid-operated valve. The power circuit for the valve solenoid has a control switch which is associated with the pneumatic motor in such manner that the switch is closed at the end of each upward or pumping stroke and is opened at the end of each downward or return stroke.

The invention further relates to arrangements and combinations of parts which will be hereinafter described and more particularly pointed out in the appended claim.

A preferred form of the invention is shown in the drawings, in which—

Fig. 1 is a diagrammatic front elevation showing the associated parts of the entire system, but with the several parts drawn to different scales;

Fig. 2 is a detail side elevation, looking in the direction of the arrow 2 in Fig. 1;

Fig. 3 is an enlarged sectional front elevation of the pneumatic motor;

Fig. 4 is an enlarged sectional front elevation of the nitrogen pump;

Figs. 5 and 6 are enlarged sectional views of certain valves shown in Fig. 4; and

Figs. 7 and 8 are perspective views of the valves shown in Figs. 5 and 6 respectively.

Referring to Fig. 1, a combustion chamber C of conventional type is shown as provided with the usual open rearward discharge nozzle N.

The chamber C is supplied with liquid oxygen from a storage tank T by a centrifugal pump P, and is supplied with gasoline or other liquid fuel from a tank T2 by a pump P2. The impellers of the pumps P and P2 are mounted on a common shaft 10 which also supports the rotor of a gas-driven turbine R.

Liquid nitrogen is stored under relatively low pressure in a tank T3, and is delivered by a reciprocating pump P3 to a heating coil 12 wound about the combustion

2

chamber C. The lower end of the heating coil is connected by a pipe 14 to a nozzle 15, and the vaporized nitrogen delivered under substantial pressure through the nozzle 15 operates the turbine R to drive the pumps P and P2.

The nitrogen pump P3 is operated by a pneumatic motor M, which motor is supplied with compressed air or nitrogen gas through a pipe 20 which connects the motor M to a valve V which has a supply pipe 22 and an exhaust connection 23. A branch pipe 24 connects the pipes 14 and 22, and usual shut-off valves permit operation with either air or nitrogen gas.

The valve V is shown as of the piston type, and with the piston rod 25 connected to a plunger 26 which extends into a solenoid coil 30. The coil 30 is connected direct to a line wire L and is connected to a second line wire L2 through a switch S.

The switch S is connected to the upper end portion 33a of an axially movable rod 33 (Fig. 3) in the motor M. The switch is closed as the rod 33 reaches the upper end of its working stroke and is opened at the lower end of the return stroke.

From this condensed description, the general operation will be apparent. When the main switch S2 is manually closed and the control switch S is also closed, the valve V will be positioned to connect the supply pipe 22 through the connecting pipe 20 to the motor M, thus producing a downward or return stroke of the pump P3 and permitting liquid nitrogen to flow into the pump P3 from the tank T3 which is under limited pressure.

At the end of the downward or return stroke, the switch S is opened, the valve V is reversed, the motor M is connected to exhaust, the moving parts of the pump P move upward on a working stroke, and liquid nitrogen is pumped into the heating coil 12 and thence as nitrogen gas at substantially higher pressure to the turbine T.

The details of construction of the pump P3, the motor M and certain associated parts are shown on Sheet 2 of the drawings and will now be described.

The pump P3 comprises a bottom plate 40 secured to the upper face of an annular member 41 mounted in an inner frame 44 slidable in a fixed outer frame F. A recessed casing member 42 is secured to the annular member 41 and has a flexible connection 43 to a feed pipe 43a extending nearly to the bottom of the tank T3.

A frame member 45 forms part of the fixed frame F and is provided with an inwardly-extending flange 46 and with guide passages 47 for the tubular side members 48 of the movable frame 44. A relatively deep shell or bushing 50 is secured to the flange 46 and extends downward therefrom and has a fixed bottom portion 51 which supports an upwardly-opening check valve V3. A bellows member 55 is connected at its lower end to the movable plate 40 and at its upper end to the fixed flange 46 and bushing 50.

A cone-shaped member 57 is mounted within the fixed shell or bushing 50 and has an upwardly-extending sleeve portion 58 secured to said bushing 50. At its upper and inner end, the cone-shaped member 57 is connected to a delivery pipe 60, which in turn is connected to the heating coil 12 (Fig. 1) previously described. A suitable check valve V4 may be provided in this connection.

The inner and movable frame 44 is secured to the lower end of the reciprocating rod 33 previously described, and this rod is alternately moved upward for a pumping stroke and downward for a return stroke.

On the downward return stroke, the valve V2 opens and liquid nitrogen will flow under the tank pressure through the valve V2 and into the space above the plate 40. The valve V3 is held closed by the pressure in the pipe 60 and coil 12.

On the following upward or working stroke, the rod 33

and frame 44 will move upward (the valve V2 being now closed), and the liquid nitrogen between the movable bottom plate 40 and the fixed bottom plate 51 will be forced out through the check valve V3 to the delivery pipe 60 and thence to the heating coil 12.

Successive portions of liquid nitrogen are thus pumped to the heating coil 12 on the upward or working strokes of the pump P. A pressure and storage tank T4 may be inserted as indicated in Fig. 1 to provide more uniform pressure in the coil 12.

The pneumatic motor M shown in section in Fig. 3 comprises an outer casing 70 having upper and lower end members 71 and 72. The lower end member 72 is connected to a sleeve 73 which is secured to the upper end of the fixed frame F (Fig. 4) of the pump P3. A by-pass 74 connects the interior of the member 72 to the tank T3 and has the usual shut-off valve. The interior of the member 72 is connected through restricted openings as shown to the interior of the casing 70.

An axial tube 75 is fixed in the upper casing member 71 and extends downward a substantial distance within the casing 70. At its upper end, the tube 75 is connected by a ring or disc 76 to an inner tube 80, which tube extends substantially downward within the casing 70 and tube 75. The lower ends of the tubes 75 and 80 have a disc 81 connecting the bottom ends thereof. A bellows member 83 is connected at its upper end to the casing end member 71 and at its lower end to a disc 85 mounted on the rod 33. The bellows 83 may preferably be formed in two parts connected by a sliding ring 87.

A compression spring 88 is positioned between the axial rod 33 and the inner tube 80, and at its lower end rests on the bottom plate 85. At its upper end, the spring engages a vented cap 90 within which the rod 33 is slidable. The supply pipe 20 previously described is connected into the upper end of the inner tube 80.

During a working stroke, the pipe 20 is connected to exhaust, and pressure from the nitrogen tank T3 pushes the bottom plate 85 and rod 33 upward and at the same time further compresses the spring 88. This feeding movement is relatively slow, as it is effected only by the flow of liquid nitrogen through the restricted openings in the lower end member 72. This relatively slow feeding movement is essential to provide enough time for vaporization of the liquid nitrogen in the coil 12 (Fig. 1). At the upper end of the stroke, the switch S is closed, pressure is admitted through the connection 20, and the combined action of the air pressure against the plate 85 and the force of the spring 88 on the plate 85 forces the plate 85 and rod 33 downward for a return stroke at a relatively much higher speed. This higher return speed permits the pumping action to be substantially continuous.

At the end of this return stroke, the switch S is opened, the pipe 20 is connected to exhaust, and the cycle is repeated.

In order to provide a delayed action of the switch S, the switch S has a pin-and-slot coupling connection 92 (Fig. 2) with the rod 33a, so that movement of the switch S takes place only at the extreme opposite ends of the movements of the rod 33. The switch S has suitable frictional contact which retains it in either open or closed position until definitely moved therefrom.

The details of construction of the valves V2 and V3 are clearly shown in Figs. 5 to 8. Each valve comprises 10 a relatively thin flexible seating member, as 95 or 96, which members are enclosed between stiffening plates 97-97a. Excessive displacement of the valve V3 is prevented by an over-hanging fixed ring 99, and similar displacement of the valve V2 is prevented by lower cross 15 bars 100.

Having thus described the invention and the advantages thereof, it will be understood that the invention is not to be limited to the details herein described, otherwise than as set forth in the claim, but what is claimed is:

20 A fluid-operated motor comprising a closed casing, a bellows member therein, restricted means to supply liquid under relatively low pressure to the space within said casing and exterior to said bellows member, and the lower end of said bellows member closing off said liquid supply when depressed, means to supply a gaseous fluid under relatively high pressure to the interior of said bellows member, a compression spring in said bellows member acting in opposition to the liquid pressure and in conjunction with the gaseous fluid pressure, a valve shift- 25 able to alternately connect the interior of the bellows member to said gaseous fluid supply or to exhaust, and a device to shift said valve which is activated by said bellows member at the upper end of the working stroke of the motor, said working stroke being effected at relatively low and controlled speed entirely by restricted flow of liquid at relatively low pressure, and the idle or return stroke of said motor being effected at relatively high speed by conjoint gaseous and spring pressure which overcomes the liquid pressure and closes off the liquid supply.
